SEALING DEVICE FOR INTERNAL GEAR PUMPS

John B. Parsons, Toledo, Ohio

Application October 7, 1943, Serial No. 505,304

1 Claim. (Cl. 103—126)

This invention relates to internal gear pumps but more particularly to the sealing of the ends of such pumps.

It is necessary that opposite ends of internal gear pumps be satisfactorily sealed in order to 5 militate against the loss or dissipation of pressure fluid, particularly from the high pressure side to the low pressure side of the pump. Heretofore such sealing has been accomplished by spring 10 pressed plates but this has not proved entirely satisfactory due to the pressure necessary for the purpose. Another procedure has been to employ 15 end caps which must be very carefully machined and fitted to the ends of the pump in order to obtain an effective seal. This is laborious and costly, thereby substantially increasing the cost of the assembly.

An object is to overcome the above difficulties and to produce a new and improved seal which is entirely automatic in operation, and reliable 20 under all conditions, liquid or fluid pressure generated by the pump being employed for this purpose, thereby substantially reducing the cost of manufacture and assembly.

For purposes of illustration but not of limitation, an embodiment of the invention is shown on the accompanying drawing in which

Figure 1 is a side elevation with parts broken away, of an electric motor driven internal gear pumping unit;

Figure 2 is a transverse sectional view on the line 2—2 of Figure 1;

Figure 3 is a plan view of the ported plate which abuts against one end of the internal gear pump;

Figure 4 is a plan view of a plate which abuts 35 against the lower end of the internal gear pump; and

Figure 5 is a spring washer or spacer for normally holding the pump and plate parts in position.

The illustrated embodiment of the invention comprises a pumping unit having a central block 10 on the upper side of which is suitably mounted an electric motor 11 and attached to the under side of the block 10 is a cup 12 which serves as a liquid reservoir. The cup 12 is held in position by a bail pivotally mounted in any suitable manner on the block 10. The electric motor 11 has an armature shaft 14 which projects downwardly into a pump housing 15 the lower end of which is open. A closure cap 16 is secured to the lower end of the pump housing 15 and is secured in place by screws 17. A packing ring 18 in the pumping housing prevents the escape of liquid along the closure cap 16.

A tube 18 depends into the reservoir 12 and terminates near the lower end thereof, liquid being pumped through this tube to a transverse passage 19 which terminates in the downwardly extending port 20 opening into the pump housing 15. In this manner it will be seen that the tube 18, passage 19 and port 20 provide the inlet to the pump housing 15. Liquid is forced from the pump housing 15 through an upwardly extending port 21 to a transverse passage 22 and thence laterally through a passage 23 to a suitable outlet nipple (not shown). A spring tensioned valve 24 is slidable in the transverse passage 23. In the event the pressure exceeds a predetermined maximum, the valve 24 will be retracted sufficiently to enable the liquid to return to the reservoir 12 through a passage 25 which communicates with a vertical tube 27 similar to the tube 18. A port 26 enables liquid to be returned to the reservoir which may be in rear of the valve 24. Reference is hereby made to my co-pending application Serial No. 452,865, entitled "Motor pump unit," for more detail description of the above described structure.

Arranged within the pump housing 15 is an internal gear pump P which may be of any suitable or desired construction. In this instance, the pump P has an outer rotor 28 formed with five notches 29, the side walls of which are flaring along curvilinear surfaces 30. The inner rotor 31 is formed with four teeth, the side walls of which are curvilinear to correspond approximately with the curvilinear surfaces 30 of the outer rotor. The arrangement is such that for each revolution of the inner rotor, the outer rotor is revolved four-fifths of a revolution. The construction and operation of the pump P is well-known to those skilled in this art and since the same forms no part of the present invention, further detail description is not considered necessary. Such pump is the well-known structure commercially known as the Gerotor pump. It will be noted that the toothed rotor 31 is fixed for rotation to the end portion of the armature shaft 14 by a key 32 but is free for axial movement along the shaft. Upon energizing the electric motor 11, the internal gear pump P is operated to draw liquid from the reservoir 12 through the inlet passages above described and discharge the same under pressure through the outlet passages above described.

It will be manifest that in order for the pump to operate efficiently, leakage of fluid must be prevented from the high pressure side of the pump to the low pressure side. It is a desideratum that

such seal be effected in a simple and inexpensive manner so that not only will an effective seal be established, but also that the wear on the parts so far as the seal is concerned, be substantially reduced or entirely eliminated. It will be understood that in the operation of the pump, both the gear parts 28 and 31 rotate so that the pump part 28 must have a nice fit within the pump housing 15. At the upper end of the pump is a relatively thin plate 33 which as shown in Figure 3, is formed with ports 34 and 35 providing the pressure fluid inlet and outlet. Adjacent the periphery of the plate 33 is an upturned lip 36 for engaging in a socket in the adjacent wall of the pump housing to hold the plate against turning movements. The plate 33 has a central aperture snugly to fit the armature shaft 14. The outer edge portion of the plate 33 fits snugly within the housing 15. An annular groove 37 is formed on the housing on the upper side of and adjacent the periphery of the plate.

The pump housing 15 is of such size that a space is provided between the lower ends of the pump rotors 28 and 31 and the closure cap 16. Arranged within this space and abutting against the lower ends of the pump rotors is a disc-like plate 39, the peripheral portion of which engages the walls of the housing. The plate 39 is preferably of metal, is relatively thin and flexible and is formed with a central aperture 40 which is substantially in alignment with the motor shaft 14. It will be manifest that the inner rotor 31 is slideable along the armature shaft 14 and the outer rotor 28 is likewise slideable in the housing. In order to sustain the weight of the rotors and the plate 39 and hold these parts in the desired position when the pump is at rest, a spring washer is arranged within the cavity or space 38 and is formed with a plurality of radial spring arms 43 which bear against the under side of the plate 39. The washer 41 has a centrally arranged concave portion which bears against the central portion of the closure cap 16. It should be understood, however, that the spring pressure exerted by the washer 41 is not sufficient to establish the desired seal.

In operation, it will be manifest that pressure fluid passing between the periphery of the disc 39 and the walls of the housing will fill the space 38 and impose an upward or axial pressure against the plate 39 and accordingly the pump rotors. The pressure imparted by the fluid in the space 38 will of course be dependent upon the pressure generated by the pump. It is desired that the plate 39 be relatively thin in order that it conform to the end surfaces of the rotors particularly in the event of any unevenness or irregularities in these surfaces so that the pressure exerted by the fluid, liquid in this case, may slightly deform the plate 39, thereby causing it to conform to the contour of these surfaces. The fluid pressure thus exerted will hold the plate 39 snugly and in sealing contact with the pump rotors 28 and 31 and owing to the greater exposed area on the under side of the plate 39 as compared to the internal area of the pump parts containing the pressure fluid, the plate 39 is held in sufficiently tight contact to produce the desired sealing action, thereby militating against leakage of the pressure fluid from the high pressure side to the low pressure side of the pump.

The central aperture 40 in the plate 39 enables the fluid pressure in this region to be equal on

both sides of the plate. Otherwise inward deformation of the plate in this region would take place due to the high pressure imposed on the under side of the plate. In the event that the plate 39 were of greater thickness and rigidity, such an aperture would not be necessary, but where the plate 39 is of relatively thin material, such aperture is desirable.

As above mentioned, the annular groove 37 which is formed in the pump housing 15 above the ported plate 33 relieves a portion of the upward thrust or pressure which is created in the space or cavity 38. This reduces the friction in that region and contributes to the efficiency of the assembly. In this connection it will be apparent that pressure fluid finds its way between the pump and the ported plate 33 and enters the annular groove 31. In this manner a downward pressure on the upper side of the peripheral portion of the plate 33 is established sufficient to relieve a portion of the upward pressure created at the opposite end of the pump.

From the above description it will be apparent that I have provided an exceedingly simple but effective seal for an internal gear pump whereby the high and low pressure sides of the pump are satisfactorily sealed from each other, the seal being effected by the pressure generated by the pump. Thus the plates are forced against the ends of the pump with sufficient pressure to effect the seal but not to such an extent as to interfere with the proper operation of the pump or to effect excessive wear on the pump parts.

It is to be understood that numerous changes in details of construction, arrangement and operation may be effected without departing from the spirit of the invention especially as defined in the appended claim.

What I claim is:

Pump sealing means comprising in combination, a housing having a cylindrical cavity provided at one end with inlet and outlet passages, mating toothed pump rotor members arranged one within the other, the outer rotor having an annular periphery providing a rotating fit with the walls of said cavity, shaft means projecting into one end of said housing and secured at its inner end portion to the inner of said rotor members for driving said rotors in eccentric relation to each other for creating expanding and contracting chambers thereby to force fluid under pressure from the inlet to the outlet passage, said rotor members being spaced slightly from the opposite end of said cavity to provide a pressure space, a flexible plate of sheet material disposed in said pressure space and abutting against the adjacent surface of both rotors, pressure fluid being adapted to pass between said plate and rotors and about the edges of said plate to said pressure space said plate having an imperforate region covering such area of the rotors creating said expanding and contracting chambers, said plate being sufficiently thin to enable the fluid pressure within said pressure space to cause the same to effect a sealing relation with the end faces of the rotors adjacent thereto, said plate being of such shape and dimensions relative to the side walls of said cavity as to maintain said region in position to cover said area, and means for normally holding said plate in abutment with said pump rotor members.

JOHN B. PARSONS.
